ROCKING CHAIR

Clara A. Ridder, Greensboro, and Byron S. Clapp, Siler City, N.C., assignors to Boling Chair Company, Siler City, N.C.

Filed Apr. 13, 1962, Ser. No. 69,697

Term of patent 14 years

(Cl. D15—6)

FIG. 2

FIG. 1

FIG. 3

FIGURE 1 is a perspective view illustrating the front and one side of a rocking chair embodying my new design;

The side of the chair not shown is the same in appearance as the side shown.

We claim:

The ornamental design for a rocking chair, substantially as shown and described.
